CLAIM

The ornamental design for a free weight, as shown and described.

DESCRIPTION

FIG. 1 is a perspective front view of a free weight.

FIG. 2 is a front view of the free weight of FIG. 1.

FIG. 3 is a rear view of the free weight of FIG. 1.

FIG. 4 is a right side view of the free weight of FIG. 1.

FIG. 5 is a left side view of the free weight of FIG. 1.

FIG. 6 is a top view of the free weight of FIG. 1; and,

FIG. 7 is a bottom view of the free weight of FIG. 1.

The boundary lines immediately adjacent to shaded areas represent a claim boundary and form no part of the claimed design. All other broken lines form no part of the claimed design. The free weight chain is shown with symbolic breaks in the width of the weights. The appearance of any portion of the article between the break lines forms no part of the claimed design.

1 Claim, 7 Drawing Sheets
